HEARSE TRAILER

Alvin E. Gottschalk, 3840 S. Seneca,
Wichita, Kans. 67217

Filed Apr. 7, 1972, Ser. No. 242,276

Term of patent 14 years

Int. Cl. D12—10

U.S. Cl. D14—17

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 13

FIG. 14

FIG. 15

FIG. 1 is a side elevational view of a hearse trailer showing my new design;

FIG. 2 is an enlarged perspective view thereof;

FIG. 3 is an enlarged front elevational view thereof;

FIG. 4 is a side elevational view of a hearse trailer showing a second embodiment of my new design;

FIG. 5 is an enlarged perspective view thereof;

FIG. 6 is an enlarged front elevational view thereof;

FIG. 7 is a side elevational view of a hearse trailer showing a third embodiment of my new design;

FIG. 8 is an enlarged perspective view thereof;

FIG. 9 is an enlarged front elevational view thereof;

FIG. 10 is a side elevational view of a hearse trailer showing a fourth embodiment of my new design;

FIG. 11 is an enlarged perspective view thereof;

FIG. 12 is an enlarged front elevational view thereof;

FIG. 13 is a side elevational of a hearse trailer showing a fifth embodiment of my new design;

FIG. 14 is an enlarged perspective view thereof; and

FIG. 15 is an enlarged front elevational view thereof. The broken lines are for illustrative purposes only and constitute no part of the claimed design.

I claim:

The ornamental design for a hearse trailer, substantially as shown and described.
